UNITED STATES PATENT OFFICE

164,366

GIRDLE

Mathias Imershein, New York, N. Y., assignor to Graceform-Camlin Corset Co., Inc., New York,
N. Y., a corporation of New York

Application March 1, 1951, Serial No. 14,344

Term of patent 14 years

(Cl. D20—2)

To all whom it may concern:

Be it known that I, Mathias Imershein, a citizen of the United States of America, and resident of the county, city, and State of New York, have invented a new, original, and ornamental Design for a Girdle, of which the following is a specification, reference being had to the accompanying drawing, forming a part thereof, in which

Fig. 1 is a front view of a girdle embodying my design; and

Fig. 2 is a rear view thereof.

I claim:

The ornamental design for a girdle, as shown.
